CLAIM

I claim the ornamental design for a BBQ lemon chicken rack, as shown and described.

DESCRIPTION

FIG. 1 is a perspective view of a BBQ lemon chicken rack, showing my new design with a chicken holding element in a first rotational orientation;

FIG. 2 is a perspective view thereof, illustrated with the chicken holding element in a second, opposite rotational orientation;

FIG. 3 is a rear elevational view of FIG. 1;

FIG. 4 is a front elevational view of FIG. 1;

FIG. 5 is a left-side elevational view thereof;

FIG. 6 is a right-side elevational view thereof;

FIG. 7 is a top plan view thereof; and,

FIG. 8 is a bottom plan view thereof.

The broken lines showing a chicken in FIG. 1 depict environmental matter and form no part of the claimed design.
